UNITED STATES PATENT OFFICE.

JAMES E. DIXON, OF WINNIPEG, MANITOBA, CANADA.

FURNACE.

Application filed November 11, 1922. Serial No. 600,437.

To all whom it may concern:

Be it known that I, JAMES E. DIXON, of the city of Winnipeg, in the Province of Manitoba, Canada, have invented certain new and useful Improvements in Furnaces, of which the following is the specification.

The invention relates to improvements in furnaces and an object of the invention is to provide a furnace with a comparatively large combustion chamber and with a comparatively long smoke chamber within the furnace casing, which smoke chamber leads the products of combustion in a circuitous path, thereby making it possible to utilize the heat units of the products of combustion for heating the cold air admitted to the air heating chamber of the furnace and subsequently passed out the hot air pipes.

A further object is to construct the air heating chamber so that the air will be circulated in close proximity to the smoke chamber, thereby taking full advantage of the heat radiated from the smoke chamber.

With the above more important objects in view the invention consists essentially in the arrangement and construction of parts hereinafter more particularly described and later pointed out in the appended claim, reference being had to the accompanying drawing in

which:

Fig. 1 is a front view of the furnace.

Fig. 2 is a side view thereof.

Fig. 3 is a vertical sectional view centrally through the furnace.

Fig. 4 is a vertical sectional view at 4—4' Fig. 3.

Fig. 5 is a horizontal sectional view at 5—5' Fig. 3.

In the drawing like characters of reference indicate corresponding parts in the several figures.

The fire pot 1 of the furnace is circular and it is provided with the customary grate 2, the fire pot being located immediately above the ash chamber 3.

Above the fire pot I locate a combustion chamber 4 having curved sides. The top of the combustion chamber communicates with a circuitous or zig-zagging smoke chamber 5 and the upper end of the smoke chamber terminates in a collecting chamber 6 which leads to the flue or outlet pipe 7.

The smoke chamber is provided with suitably positioned clean out doors 8 and from

the above construction it will be obvious that the products of combustion, arising from the combustion chamber, will pass upwardly through the smoke chamber in a circuitous path and will finally pass out through the smoke pipe.

The parts above described are enclosed within a sheet metal casing 9 similar to that employed on present furnaces, the casing being provided with an ash door 10, fire door 11, cold air inlet pipes 12, and hot air outlet pipes 13. This casing is substantially rectangular, as best shown in Fig. 5 and within the casing I locate baffle plates 14 which are carried by the casing and are spaced from the smoke chamber and combustion chamber and are shaped to follow the contour of the combustion chamber and smoke chamber. These baffle plates keep the cold air admitted to the bottom of the furnace through the pipes 12, in close proximity to the smoke chamber and the said cold air is efficiently and effectively heated prior to passing out through the distributing pipes 13.

Obviously, the combustion chamber and the smoke chamber give a comparatively large heat radiating surface within the furnace which is effectively utilized to heat the cold air admitted to the bottom of the furnace.

The casing is provided with clean out doors 15 opposing those 8.

What I claim as my invention is:

A furnace comprising a fire box, an outer casing provided with a smoke outlet, a pair of plates secured to opposite sides of the casing to extend upwardly therealong from a point above the fire box, one of said plates being formed with reverse bends affording spaced baffles and sloping curvilinear surfaces at the sides of each baffle, the other plate being similarly formed with a single reverse bend affording an inwardly projecting baffle staggered with respect to the baffles of the other plate, a combustion chamber closing the top of the fire box and a flat tubular conduit extending from the top of the combustion chamber to the smoke outlet and disposed to pass between the inwardly directed baffles in spaced relation thereto, said conduit being shaped to follow the contour of the passage afforded between the aforementioned plates and serving to act as a further check to the direct ascent of air sup-

plied to the lower portion of the casing, said air being directed by the baffles into contact with opposite sides of the smoke conduit so as to be heated by the latter, said conduit being provided at the bends thereof with clean-out openings opposing corresponding openings formed in the outer casing.

Signed at Winnipeg, this 11th day of October, 1922.

JAMES E. DIXON.

In the presence of—
GERALD S. ROXBURGH,
M. B. KELLEHER.
